COMBUSTION CHAMBERS FOR PISTONS

Siegfried Meurer, Nurnberg, Germany, assignor to Maschinenfabrik Augsburg-Nurnberg A.G., Nurnberg, Germany
Original application June 9, 1958, Ser. No. 740,908, now Patent No. 2,975,773, dated Mar. 21, 1961. Divided and this application Dec. 8, 1960, Ser. No. 74,651
Claims priority, application Germany July 6, 1957
6 Claims. (Cl. 123—32)

This invention relates to combustion chambers for pistons. In particular, the invention is directed to combustion chambers for self-ignition engines.

This application is a division of my application Serial No. 740,908, filed June 9, 1958, for "Combustion Chambers for Pistons," now Patent 2,975,773, issued March 21, 1961.

The piston of this invention is designed to operate in self-ignition engines such as disclosed in U.S. Patent No. 2,907,308. In such engine, the liquid fuel is injected into a hollow combustion chamber in the piston. The injection is made in such a way that the major portion of the fuel travels over a short free path and is applied immediately to the wall of the combustion chamber. After striking the chamber wall, the fuel spreads out as a film over a part of the wall. The remaining minor portion of the fuel is atomized directly in the air in the chamber and is self-ignited for igniting the fuel vaporized from the film of fuel. Combustion air is swirled over the film of fuel to vaporize the same.

In these engines, it is desirable to have the fuel cover as much as possible of the chamber wall. If the chamber, as in former pistons, is spherical or ellipsoidal and the fuel strikes the wall at a sharp angle, the fuel is spread as a film in a satisfactory manner. Because of the kinetic energy of the fuel, it has a tendency to spread peripherally about the wall of the combustion chamber. However, in these chambers, the spreading of the fuel is handicapped by the concave curve of the spherical or ellipsoidal chamber. Such chamber forms act in the nature of a groove with the fuel tending to flow along the bottom thereof and not completely spread out.

The object of this invention is to produce a combustion chamber formed as a body of rotation and having a shape such that the fuel will spread out evenly in all directions on the wall of the chamber.

In accordance with the invention, the combustion chamber is in the form of two oppositely directed conical chamber portions, with the two portions connected at their bases. A chamber so constructed has been found to improve the cold starting of an engine. This is because of the sudden change given the direction of the spreading fuel over the joint between the two conical sections. The fuel at this point is momentarily detached from the wall. Consequently, the air swirling across the separated fuel atomizes the fuel which is of special advantage for high boiling point fuels. A similar effect can be obtained if the chamber wall and bottom are of spherical shapes with different curvatures. In the latter construction, as compared to the two conical portion construction, the momentary separation of the fuel from the film can be accomplished closer to the opening into the combustion

2

chamber so that the atomization is more effective in the starting of the engine.

When the combustion chamber is in the form of two conical portions, these conical portions can be symmetrical and axially aligned. However, in a modified construction, the conical portions can be either non-axially aligned, or can be axially out of line, or can be non-symmetrical for purposes of forming fuel films desirable for certain combustion processes.

10 The means by which the objects of the invention are obtained are described more fully with reference to the accompanying drawings, in which:

FIGURE 1 is a longitudinal cross-sectional view through a piston in a cylinder with the piston having a combustion chamber according to this invention; and

15 FIGURES 2 and 3 are similar views of respective modified forms of the combustion chamber.

As shown in FIGURE 1, the combustion chamber 1 is positioned in the piston head of piston 2, the chamber being coaxial with the axis of piston 2 and cylinder 3. A nozzle 4 is inclined in the cylinder head 4a above the combustion chamber. The major portion of the injected fuel is applied to the combustion chamber wall by several fuel jets 4b which are directed at a sharp angle toward the wall and form a film thereon. This film is vaporized from the wall and mixed with the air swirling in the chamber to produce a combustible fuel mixture. The minor portion of the fuel is atomized immediately in the air swirling in the chamber. This atomizing is accomplished by either deflecting a part of the injected fuel into the air or by a special ignition jet, not shown. As the fuel leaves the nozzle, it has a kinetic energy which moves the fuel circumferentially around and upon the combustion chamber wall.

30 35 As shown in FIGURE 1, the combustion chamber 1 is connected to the surface of the piston by means of a cylindrical neck 9 and is composed of two oppositely directed conical portions 12 and 14, respectively, in the form of truncated cones with their bases joined on the line 16. Chamber 1 is coaxial with the longitudinal axis 40 of the piston. Along the line 16, the wall of the chamber is interrupted to form an irregular surface which causes the fuel being applied to be momentarily separated from the chamber wall. This separated fuel mixes 45 with the air swirl in the chamber and thus causes an atomizing of at least a part of this separated fuel.

When it is desired to apply the fuel to particular wall areas, such can be accomplished by the arrangement of the portions of the chamber wall. As shown in FIGURE 2, the conical portions 12a and 14a, instead of being coaxial, are displaced with respect to each other as by having the two axes at an angle to each other. Alternatively, as shown in FIGURE 3, the conical portions 12b and 14b are made asymmetrical with respect to each other.

50 55 Having now described the means by which the objects of the invention are obtained,

I claim:

1. In a piston having a combustion chamber for receiving a film of fuel injected upon the wall of the chamber, said fuel being then vaporized and burned, the improvement comprising a downwardly directed combustion chamber extending from the top surface of the piston into the piston body, said chamber having wall surfaces in

the form of a pair of oppositely extending truncated cones with their larger bases joined to one another.

2. In a piston as in claim 1, said pair of truncated cones being symmetrical and coaxial.

3. In a piston as in claim 1, said pair of truncated cones being non-coaxial.

4. In a piston as in claim 1, said pair of truncated cones being asymmetrical with respect to each other.

5. In a piston as in claim 1, said pair of truncated cones being non-coaxial and non-symmetrical with respect to each other.

6. In a piston as in claim 1, further comprising a cylindrical neck between the top surface of said piston and said combustion chamber.
